UNITED STATES PATENT OFFICE.

THOMAS CLYNE, OF DETROIT, MICHIGAN; ELLEN CLYNE ADMINISTRATRIX
OF SAID THOMAS CLYNE, DECEASED.

PIANO-STOOL.

SPECIFICATION forming part of Letters Patent No. 595,847, dated December 21, 1897.

Application filed November 14, 1896. Serial No. 612,118. (No model.)

To all whom it may concern:

Be it known that I, THOMAS CLYNE, a citizen of the United States, residing at Detroit, in the county of Wayne and State of Michigan, have invented certain new and useful improvements in Piano-Stools; and I do hereby declare the following to be a full, clear, and exact description of the invention, such as will enable others skilled in the art to which it applies to make and use the same.

This invention has reference to a novel construction in a piano-stool, the object being to provide a device of this kind that can be adjusted vertically and its seating capacity increased or diminished quickly and readily.

It consists in the novel features of construction hereinafter fully described and specifically claimed.

In the accompanying drawings, forming a part of this specification, Figure 1 is a vertical longitudinal section of a piano-stool constructed in accordance with this invention. Fig. 2 is a bottom plan view, the feet being removed. Fig. 3 is a vertical transverse section.

Referring now to said drawings, 1 indicates the upright post, provided with feet 2. The said post 1 is provided with a longitudinal guide-opening 3 to receive the sliding spindle 4 of the seat. The said spindle 4 is provided with notches or teeth 5, that are engaged by a spring-actuated detent 6, mounted upon and operated by a rod 7, fastened to the seat and passing through an eye in said detent. The lower portion of said rod 7 is situated within and extends through an opening in the post 1 and has a slight lateral play therein, whereby the detent is drawn away from the toothed spindle. The upper end of this rod 7 is provided with a handle 8, moving in guides in the lower face of the seat, and by means of which the detent can be operated to raise or lower the seat. The seat 8' is provided at its ends with hinged wings 9. The hinges between these wings and the said seat consist of guide loops or eyes 10, that are situated within guide-grooves 11 upon the seat and through which extend the guide-rods 12, fastened to the seat and situated within said grooves 11. In this way it

will be seen that the wings cannot only swing with relation to the seat, but also can move inwardly, whereby their outer faces can stand flush with the ends of the seat when they swing downwardly, as shown in dotted lines 55 in Fig. 1.

Mounted upon the lower face of the seat and within suitable guides are the spring-actuated plungers 13, that serve both to support the wings and to move them to a horizontal position. These plungers consist of sliding frames, the outer or cross piece of which is provided with a stem 14, that slides at its inner end through a casting 15 upon said seat, while a spring 16 serves to press 65 these plungers outwardly. The wings 9 are provided with downwardly and inwardly projecting hooks 17, situated to engage the outer ends of the plungers when they are extended. To hold a plunger at the inward 70 limit of its movement and the wings in a depending position, a spring-catch 18 is mounted upon the lower face of the seat and is controlled by a handle 19, near one side of the seat. This spring-catch 18 is situated to engage a projection 20 upon the wing when said wing is in a depending position, as shown in dotted lines, Fig. 1. When it is desired to raise one of the wings, it is necessary only to pull upon the spring-catch 18, which releases 75 the wing, whereupon the spring 16 forces the plunger outwardly and lifts the wing to a horizontal position, while at the same time it engages the hook or finger 17 and serves to relieve the hinges of the wings from the strain 80 of a person sitting upon the seat, as clearly shown in Figs. 1 and 2.

In the foregoing description it will be seen that I provide a piano-stool which can be readily raised and lowered and whose sitting 90 capacity can be quickly enlarged or decreased.

Having thus described my invention, what I claim as new, and desire to secure by Letters Patent, is—

1. The combination with the seat, of a 95 spring-actuated plunger, a hinged wing secured to said seat and provided with a depending hook or finger situated in the path of said plunger, substantially as described.

2. The combination with a seat provided 100

with a spring-actuated plunger and with a spring-catch, of a pivoted wing situated in the path of said plunger and provided with a projection to engage said spring-catch, substantially as described.

3. The combination with a seat, of a wing hinged thereto, said hinged connection between said wing and seat consisting of eyes upon said wing situated within guide-grooves upon said seat, and engaged by guide-rods

situated within said guide-grooves, substantially as described.

In testimony whereof I have signed this specification in the presence of two subscribing witnesses.

THOMAS CLYNE.
